ATTORNEY

UNITED STATES PATENT OFFICE.

LEONARD WOODS, OF ST. LOUIS, MISSOURI.

PISTOL.

1,073,312.

Specification of Letters Patent. Patented Sept. 16, 1913.

Application filed November 4, 1912. Serial No. 729,401.

To all whom it may concern:

Be it known that I, LEONARD Woods, citizen of the United States, residing at 3644 Botanical avenue, in the city of St. Louis 5 and State of Missouri, have invented certain new and useful Improvements in Pistols, of which the following is a specification.

This invention relates to certain new and 10 useful improvements in pistols, the peculiarities of which will be hereinafter described and claimed.

The object of my invention is to provide a pistol that can be carried in the vest pocket 15 like a watch, is as readily accessible, and appears like a watch, whereby it may be presented and fired at a highwayman while apparently merely obeying his command to "hand over your watch and be quick 20 about it"!

To this end my improvements have reference to a round, flattened casing and stem with adjacent projection, forming the stock, barrel and trigger, respectively, of a pistol; 25 have reference to a trigger adapted to be operated without suspicious movement of the finger; have reference to a barrel lining adapted to act as a shell retainer and extractor; and have reference to other points 30 of detail hereinafter described and claimed.

In the accompanying drawings on which like reference letters indicate corresponding parts, Figure 1 represents a pistol exemplifying my improvements, and indicating the 35 manner in which it is held for use; Fig. 2 a muzzle view of the same; Fig. 3 an interior view of the stock and a longitudinal section of the barrel and its lining; Fig. 4 a cross section on the line A A of Fig. 3; 40 and Fig. 5 a detail of the barrel lining.

The letters B C designate the back and front respectively of a casing similar in size and shape to an ordinary watch case, provided with an overlapping lip D to form a 45 joint at the circumferential edge, and held in matching position by screws E passing through corresponding bosses F in the front and back respectively; the front is provided with a crystal and dial face of a watch 50 representing preferably an open faced watch as shown in Fig. 1, but may be of other design. On the neck of the stem at the front side is a loop G to receive the snap hook of a watch chain. The loop is at the front side 55 so that the chain may not interfere with the muzzle which is formed to represent the

stem of a watch as shown in Figs. 1 and 2. One side of the casing, preferably the back, is provided with a central cylindrical barrel H having screw threads at its outer end, constituting the neck of the stem, which threads are engaged by matching threads on a lining for said barrel which consists of a tube I having a milled head at its outer end corresponding to the stem of a watch 60 and adjacent to said screw threads that engage with those of the barrel. This tube lining is chambered at its inner end as usual to receive a cartridge J to be inserted therein. The milled head constitutes the muzzle 65 of the pistol and the tube I is a close fit within said barrel, and of such relative length that it presses the head of the cartridge firmly against the rear wall of the barrel in which is formed a tapered opening K into which enters the tapering point

L of the hammer M which is pivoted to a boss on the back casing by a screw N. A spring O engages a notch in the hub of said hammer, at the opposite side of the hub 70 from the point L and is fixed in a slot P of the back casing. This spring has a tendency to straighten out, and a stop pin Q maintains said spring slightly bent upward as shown in Fig. 3, so that a backward 75 movement of the hammer head will cause the spring to be bent upward in a reverse curve as indicated by dotted lines in Fig. 3. This form of spring is preferred on account of the increasing force with which it 80 acts on the hammer as the spring comes nearer to its slightly bent position from that shown in dotted lines, but other forms may be employed. The actuating mechanism for said hammer consists of a round rod R 85 mounted in a groove parallel to said barrel preferably formed half in the back casing and half in the front casing by matching projections S and T respectively, as shown in Figs. 3 and 4. The projection T from the 90 front extends from the end of the barrel toward the stem as shown in Fig. 3, and forms a guide for said trigger R adapted to slide therein when the forefinger presses against the milled upward-turned end U 95 which is normally located at the outer end or muzzle. By reference to Fig. 1 it will be seen that the forefinger easily assumes a position on the trigger end U and the pressure slides the trigger backward to the 100 dotted position and brings the forefinger 105 safely back of the muzzle. The inner end

2 of the round trigger rod R has a square-topped head with a downward projection V adapted to engage the upper end of said hammer as shown in Fig. 3, and of such 5 overlapping engagement that the sliding, backward action of the trigger will diminish such engagement until the hammer head slips from the trigger head V as indicated by dotted lines in Fig. 3, whereupon 10 the spring Q, flexed by such backward action, will drive the point L of the hammer against the cap of the cartridge which is firmly held in the barrel by the lining I as previously described. 15 Upon the flat top of the trigger head V is adapted to bear a spring W having a downward tendency, and secured in a slot X of the back casing. This spring tends to maintain the head and hammer in proper 20 engaging position as shown in Fig. 3, but allows the trigger rod R to be turned one quarter of a revolution by means of the end U, whereby the trigger may be drawn outward again and the head V will pass over 25 the hammer head and be rotated downward in front of the hammer again as shown in full lines. Referring to Fig. 2 it will be seen that the milled muzzle forming the stem of the apparent watch and the outer 30 end of the barrel are cut away at 2 to allow this quarter rotation of the trigger as above described. This actuating mechanism has the advantage of simplicity of parts and operation, but I do not confine myself to the 35 exact form shown.

In the form shown, the re-loading of the pistol is performed when the trigger is in its dotted position, thereby allowing the rotation of the milled head to disengage the 40 matching screw threads to withdraw the lining and shell without interfering with the trigger. After loading, the trigger is pulled outward to its operative position as above described. 45 It is evident from the above description that this pistol has the element of safety from accidental discharge when the trigger head V is located behind the hammer head. It may therefore be safely carried in the 50 pocket during the day, as well as rendered safe from careless manipulation by others elsewhere. Furthermore when the trigger is set to its operative position it is not liable to receive sufficient pressure accidentally to 55 discharge the cartridge. It is preferred in this application to present a single shot pistol of simple and yet effective construction and design which will allow it to be presented and discharged at a highwayman without 60 his being aware that such action will take place, and at such close range and with such opportunity of aiming it that a single shot will suffice.

While the pistol shown herein is a muzzle loader, I do not confine myself to this particular; also the barrel may be adapted to dispense with the herein described lining without departing from the spirit of my invention. 65

Having thus fully described my invention, 70 what I claim as new and desire to secure by Letters Patent, is:

1. An improved article of manufacture consisting of a pistol having a stock provided with a barrel hidden therein and provided with screw threads at its outer end, a lining for said barrel chambered to receive a cartridge at its inner end having matching screw threads near its outer end, and a milled head to effect screw engagement and disengagement, whereby a contained cartridge is firmly held at the inner end of said barrel and its lining, and actuating trigger and hammer mechanism for exploding said cartridge. 85

2. An improved pistol comprising a round edged, disk-like stock having only a short stem-like barrel projecting from the stock, a trigger rod slidably mounted with its outer end directly adjacent to the muzzle of said barrel with its end turned up to facilitate operating it by the forefinger while the thumb and other fingers embrace the edge of the stock substantially as indicated, and operating mechanism adapted to be actuated by said trigger rod when pushed in by the forefinger, which is thereby brought safely back of the muzzle. 90

3. An improved pistol comprising a flattened, round edged disk-like stock provided with a short projecting barrel bearing the same relative proportion to the stock as the stem and casing of a watch respectively, and without other projection than a trigger rod slidably mounted in a groove in the outside of said barrel with the finger end of said rod adjacent to the muzzle, and a loop adjacent to the muzzle adapted for attachment to a watch chain, to facilitate carrying safely in the pocket, removing it therefrom, and operating said trigger, substantially as and for the purpose described. 100

4. A pistol comprising a stock, a barrel, a spring-actuated hammer, and a slideable spring-controlled rod mounted in guides, and provided with a down-turned end normally engaging the front of said hammer in operative position, but capable of partial rotation substantially as and for the purpose described. 115

In testimony whereof I have affixed my signature in presence of two witnesses.

LEONARD WOODS.
